METHOD OF PRODUCING LACE STRIPS

Nathan Kaminow, Long Beach, N. Y.

Application January 2, 1941, Serial No. 372,940

1 Claim. (Cl. 96—24)

This invention relates to the simultaneous manufacture of fabric strips such as cotton, linen, silk or viscose laces. Heretofore, it has been the general practice to produce netted fabric strips of this nature by netting a fabric made up of a plurality of longitudinally extending strip-forming portions joined together in side by side relation by threads of the same material as that from which the fabric is made and then to subsequently separate the strip-forming portions by cutting and drawing out sections of the connecting thread to separate the strip-forming portions of the fabric from each other to produce the separate strips. This method entails a considerable amount of time and labor and frequently results in distortion or puckering of the strips.

In order to overcome the objections and disadvantages of the aforementioned method, the present invention is directed to an improved method which consists in producing a netted fabric made up of a plurality of longitudinally extending strip-forming portions joined together in side by side relation by a soluble connection between the adjacent edges of adjacent strip-forming portions and then subjecting said fabric to the action of a solvent for said connection so as to dissolve the same and thereby disconnect said strip-forming portions into a plurality of separate strips.

The invention more particularly comprehends a method of simultaneously manufacturing a large number of netted fabric strips which consists in producing a netted fabric made up of a plurality of longitudinally extending strip-forming portions of a material insoluble in cellulose ester solvents and with the strip-forming portions secured together in side by side relation by a connection soluble in cellulose ester solvents and then subjecting the fabric to the action of a solvent for dissolving the soluble connection between the strip-forming portions.

With the foregoing and other objects in view, reference is now made to the following specification and accompanying drawing in which:

Fig. 1 is a fragmentary plan view of a netted fabric constructed in accordance with the invention and illustrating the strip-forming portions secured together by a solvent connection.

Fig. 2 is a diagrammatic sectional perspective view illustrating the manner in which the fabric is subjected to the action of the solvent and the strip-forming portions separated and wound.

In carrying out the method, the usual lace making machine, not shown, may be employed to produce a netted fabric 10 which is made up of a plurality of strip-forming portions 11 disposed

in side by side relation and joined together longitudinally thereof by threads 12 which connect the adjacent edges of adjacent strip-forming portions 11. By way of illustration, the netted fabric 10 consists of three strip-forming portions 11 but as produced, the same is of a width to provide a large number of such portions which are of a width corresponding to the setting of the machine. In a machine set for producing strip-forming portions of approximately one inch in width, the netted fabric 10 may be of a width to provide one hundred and two such strip-forming portions.

In accordance with the invention, the strip-forming portions 11 are of a material insoluble in cellulose ester solvents, such as cotton, linen, silk or viscose threads or combinations thereof, while the connecting threads 12 are soluble in cellulose ester solvents such as acetone, chloroform, alcohol-ether, methyl acetate and amyl acetate depending upon the character of the threads used which may be cellulose acetate or cellulose nitrate.

The netted fabric 10 is subjected to the action of a cellulose ester solvent in any desired manner, such as by immersing the same therein, but as illustrated, the fabric is drawn between revolving rollers 14 and 15 each of which is surrounded by a sheath 16 of felt or other absorbent material.

The rollers 14 and 15 are journaled for rotation in juxtaposition to a receptacle 17 for containing the solvent with the lower portion of the lower roller 14 of each pair immersed in the solvent which is taken up by the absorbent sheaths 16 and applied to the fabric. The connecting threads 12 being subjected to the action of said solvent, readily dissolve so as to disconnect the strip-forming portions 11 into a plurality of separate strips which are wound upon

40 a roller 18 journaled for rotation in timed relation with the rollers 14 and 15. The solvent taken up by the rollers, together with the solution resulting from the dissolving of the connecting threads in the solvent, is returned to the receptacle 17 by the continuous turning of the rollers and the supply of solvent in the receptacle replenished as required. The roller 18 may be driven by any desired means so as to wind the lace strips thereon and draw the fabric 10 between one or more pairs of the rollers 14 and 15.

What is claimed is:

In a method of simultaneously producing a quantity of lace strips, the steps of manufacturing a netted fabric made up of a quantity of longitudinally extending strip-forming portions dis-

posed in side by side relation and of a material insoluble in cellulose ester solvents and with the strip-forming portions secured together longitudinally thereof by a connection joining adjacent edges of adjacent strip-forming portions and of a material soluble in cellulose ester solvents and thereafter passing said fabric between absorbent surfaced rollers coated with a cellulose ester

solvent for applying to and dissolving the connection joining the adjacent edges of said strip-forming portions and then separating said strip-forming portions in spaced apart relation and 5 winding the same upon a member rotating in timed relation with said rollers.

NATHAN KAMINOW.
